UNITED STATES PATENT OFFICE.

CHARLES FRANKLIN BRADBURN, OF DELMER, ONTARIO, CANADA.

VALVE.

1,215,769.

Specification of Letters Patent. Patented Feb. 13, 1917.

Application filed July 7, 1916. Serial No. 108,013.

To all whom it may concern:

Be it known that I, CHARLES FRANKLIN BRADBURN, of the village of Delmer, in the county of Oxford and Province of Ontario, 5 Dominion of Canada, have invented certain new and useful Improvements in Valves; and I hereby declare that the following is a full, clear, and exact description of the same.

- 10 The ordinary type of sleeve valve engine under rapid changes in load and consequent fluctuations in thermal conditions, develops variations in the rates of expansion of the sleeves, cylinder walls, liners, etc., of the 15 engine, and from this condition, serious binding effects result between these parts, as well as from carbonization and from oil residue in combustion engines.

Moreover, the heavy gas pressures to 20 which sleeves, filling the entire engine cylinder are subjected, the severe raking effect of the contained engine piston, the fact that such sleeves must be actuated through connections acting to one side of the sleeve, and 25 the further necessity of the valve mechanism being entirely within the engine cylinder, all constitute serious disadvantages.

A principal object of the present invention, a piston and sleeve valve for any type 30 of engine, and particularly for internal combustion engines, is the retention of all the advantages of the sleeve type of valve, and the avoiding of the above-mentioned, and certain other, inherent disadvantages.

35 Briefly, the invention comprises a valve casing, containing a cylindrical valve chamber, mounted upon an engine, and having two ports preferably arranged as annular cavities, inhaust and exhaust, the planes 40 containing the ports being displaced axially of the chamber in respect of each other, a valve sleeve reciprocating within the valve chamber and carrying two semi-annular rows of ports, inhaust and exhaust, with a 45 spacing between them axially of the sleeve, having a correspondence with those of the valve casing, and a double piston reciprocating within the valve sleeve, one piston being an ordinary or closed piston with piston 50 or packing rings, and the other piston being hollow or open, comprising a spider

carrying rings, there being a spacing between the pistons equal to the spacing between the two semi-annular rows of ports. When the spacing between the pistons registers with a line of ports in the sleeve and with one of those of the valve chamber, the inhaust or exhaust occurs, as the case may be. 55

The double piston and the split sleeve are driven by eccentrics, or by crank and eccentric respectively, from a half speed valve shaft above them, the crank of the piston being set in advance of the eccentric of the sleeve, this angular advance equaling, preferably, 30 degrees of rotation. 60

65 In the drawings:

Figure 1, is a longitudinal section showing a cylindrical valve chamber mounted upon an engine cylinder;

Fig. 2, is an elevational view of the split 70 valve sleeve which operates in the valve chamber, showing two rows of ports, one for inhaust and the other for exhaust;

Fig. 3, is a plan view of the upper end of the valve sleeve shown in Fig. 2; 75

Fig. 4, is an elevational view of the double piston which operates within the valve sleeve;

Fig. 5, is a plan view of the lower end of the piston; 80

Fig. 6, is a sectional elevation showing the valve assembly and its connections, in the initial phase of the valve's cycle of action;

Fig. 7, is a fragmentary elevation of the valve connections, at right angles to Fig. 6; 85

Fig. 8, is a sectional view showing the double piston at 10 degrees of rotation and the valve sleeve at 340 degrees, during the cycle of action;

Fig. 9, is a sectional view showing the 90 valve positions, with the double piston at 6 degrees and valve sleeve at 36 degrees;

Fig. 10, is a sectional view with the piston at 90 degrees and the valve sleeve at 60 degrees; 95

Fig. 11, is a sectional view with the piston at 180 degrees and the valve sleeve at 150 degrees;

Fig. 12, is a sectional view with the piston at 270 degrees and the valve sleeve at 240 100 degrees;

Fig. 13, is a sectional view with the piston

at 310 degrees and the valve sleeve at 280 degrees;

Fig. 14, is a sectional view with the piston at 350 degrees and the valve sleeve at 320 degrees; and,

Fig. 15, is a sectional view with the piston at 100 degrees and the valve sleeve at 70 degrees.

Like characters of reference refer to like parts throughout the specification and drawings.

In these figures, the direction of motion of the valve piston and sleeve and their connections, the engine piston, and the passage of vapor or of gas, are all indicated by suitable arrows.

The drawings are to some extent diagrammatic and not necessarily working drawings, and for this reason it has not been thought necessary, for example, to show a cooling system or other of the less essential features of an internal combustion engine, neither is the driving gear leading to the valve shaft shown, as such gear is not an integral portion of the invention.

In Fig. 1, *a* is the cylindrical valve casing, containing a valve chamber *a'*, mounted upon the engine cylinder *b* and having two ports, preferably arranged as semi-annular cavities, *c* being the inhaust and *d* being the exhaust, these ports being separated by partitions *e*. The valve chamber is open at the top to facilitate cooling, though this is not essential, and carries a yoke *f* which furnishes bearings for the valve rods.

In Figs. 2 and 3, is shown the valve sleeve *g*, carrying two rows of ports, *h* for inhaust and *i* for exhaust, with a spacing axially of the sleeve between the rows equal to the depth of the double piston spacing. This sleeve is split along a diametral vertical plane *j*, extending from the lower edge of the sleeve upwardly to the drillings *k* near the upper edge. The purpose of this feature is to give to the sleeve an approximation of the properties of a piston ring, at least beneath the points of drilling, so that, in part because of its elasticity, and in part because of internal gas pressure, there may be no leakage between the sleeve and the wall of the valve chamber, and no binding between the same because of inequalities in expansion. The above feature is extremely important, though not an essential element of the invention.

The sleeve *g* is provided at its upper extremity with an irregular-shaped member *l* which constitutes a reinforcing band or collar carrying a lunular-shaped web *m*, having a bushing *n* which forms an attachment for the rod *o*, which latter carries a connection or bearing *p* for the driving eccentric rod.

In Fig. 4 is shown the double piston, of which the upper piston *q* is closed, and the lower piston *r* is hollow or open, *s* being the

spacing between the two pistons and *t* the piston rod having a bearing *u* for the connecting rod from the driving crank.

Fig. 5 shows the lower end of the lower piston, *t* being the piston rod, *v* the spider and rim, and *w* the piston rings. The piston *r* is adjacent to the lower or engine end of the valve chamber and is made hollow for the free passage of the vapor and gas between the piston spacing and engine cylinder.

A complete understanding of this invention is practically impossible unless definite relative values be assigned to the more essential valve parts and to the movements of the same, and while different relative values might be chosen in the manipulation of the times of inhaust closing and exhaust opening, the former through changes in the location of the lower edges of the inhaust ports of the sleeve, and the latter through changes in the location of the upper edges of the exhaust ports, the other edges in each case remaining unchanged, and still greater changes effected through the shifting of the angular distance between the crank of the valve piston and the eccentric of the valve sleeve, the values here given are those which at the present time it is believed will give the highest average results or efficiency in high speeds, and this, of course, must take into consideration, fuel consumption, speed, flexibility, stresses and wear.

Assuming the radius of the valve crank and the throw of the eccentric to be 1000 units of space, and the angular distance between crank and eccentric to be 30 degrees, the piston being in advance, then the valve displacement, or displacement of sleeve and of piston, will be 1000 units each, or the valve travel 2000 units, and the piston being in advance of the sleeve, the respective lines of travel of these two principal moving parts may be made to overlap, the piston and sleeve moving at certain times in opposite directions and at certain other times in the same direction and with varying relative speeds, as will become more apparent in discussing the valve assembly and the valve positions in operating throughout the complete cycle of the valve's action.

On the above basis of valve travel and angular distance between crank and eccentric, the following will be the relative dimensions of the essential parts of the valve mechanism:

Vertical depth of inhaust cavity of valve chamber equals 827 units;

Vertical depth of exhaust cavity of valve chamber equals 1066 units;

Vertical depth of inhaust ports of valve sleeve equals 316 units;

Vertical depth of exhaust ports of valve sleeve equals 333 $\frac{1}{3}$ units;

Vertical displacement between upper edges 130

of inhaust ports and lower edges of exhaust ports equals 338 $\frac{1}{4}$ units;

Length of sleeve above exhaust ports equals 1533 units;

5 Length of sleeve beneath inhaust ports equals 983 units;

Length of upper valve piston equals 666 $\frac{3}{4}$ units;

10 Length of lower valve piston equals 333 $\frac{1}{4}$ units;

Depth of spacing between pistons equals 333 $\frac{1}{4}$ units;

Displacement or lap of lines of travel of double piston and valve sleeve equals 134 units;

15 *i. e.* must equal 134 units since this is the amount the one member will continue to travel in either direction after the other has reversed its motion and begun traveling in the opposite direction. This value, of

20 course, equals the difference between the sine of an angle of 90 degrees and the sine of an angle of 60 degrees, since 30 degrees is the angular or phase difference of piston and sleeve, and in this case, we take the sine of

25 90 degrees as equaling 1000 units, this being the radius of our two equal reference circles, viz: crank and eccentric, or displacement of lines of valve travel equal sine 90 degrees minus sine 60 degrees, equal versed sine 30

30 degrees, equal 134 units.

Figs. 6 and 7 show the valve assembly in which the valve sleeve *g* is shown within the valve chamber *a'*, and the double piston within the sleeve, and with the driving con-

35 nections shown above the valve chamber.

The inhaust ports *h*, of the sleeve, face the inhaust cavity *c* of the valve chamber and the exhaust ports *i* face the exhaust cavity *d*, while the lines of cleavage or split lines *j*

40 of the sleeve are opposed by the partitions *e* of the valve chamber. In Figs. 6 and 7, the driving connections are shown in the same phase.

In Fig. 6, *z* is the engine piston, *a''*, *b''*

45 are spark plugs in the head of the engine cylinder *b*, while in each of the Figs. 6 and 7, *c''* indicates the half speed valve shaft or shafts, *d''* the crank wheel or disk, *e''* the crank, *f''* the eccentric, *g''* the eccentric rod,

50 and *h''* the crank or connecting rod. The crank pin extends through the eccentric, and the piston rod *t* of the double piston passes through the opening formed by the lunar-shaped web *m*, shown in Fig. 3 in the top of

55 the valve sleeve *g*.

In Fig. 6, the valve sleeve is shown within the valve chamber and the double piston within the valve sleeve in proper relationship to each other and to their connections,

60 in the initial phase of the valve's cycle of action.

The views given in Figs. 6 and 7 are taken as implied, with the double piston crank at 360 degrees (0 degrees) of rotation and the 65 valve sleeve eccentric at 330 degrees ro-

tation, *i. e.*, retarded by an angular distance of 30 degrees. Hence the double piston will be at the upper limit of its travel, and the valve sleeve lagging by approximately 134 space units. This position of the valve corresponds to the end of the fourth or exhaust stroke of the engine, and the beginning of the first or inhaust stroke.

On the basis previously mentioned, the depth of the double piston spacing and that of the exhaust ports of the valve sleeve, as also the clear vertical displacement between inhaust and exhaust ports of the valve sleeve, is made equal to $\frac{1}{4}$ valve travel, while the depth of the inhaust ports of valve sleeve 70 is made equal to 316 units.

All the above measurements might under certain conditions be taken equal to,

$$\frac{\text{valve travel}}{2\pi}$$

85

but we need not discuss this or other cases, save the one herein presented.

On the present basis the initial or reference line of valve travel marked 0—0, Fig. 90 6, will, when the double piston crank is at 0 degrees of rotation, pass through the upper edge of the line of inhaust ports *h* of the valve sleeve *g*, and through the lower boundary of the piston spacing *s* of the double 95 piston, while the upper edge or boundary of the inhaust cavity *c* of the valve chamber *a'* will lie on a line, or in a plane, 134 units above the initial reference line.

It may be noted that reference lines 0 to 100 2000 represent the travel of the lower boundary of the double piston spacing, while above these lines are other reference lines preceded by *x* and extending upwardly to *x2333*, and beneath are lines preceded by *y*, 105 110 and extending downwardly to *y1166*, the three sets of lines being continuous.

From the above, it will be seen that the upper boundary of the inhaust cavity *c* will fall upon the line *x134*, and (having regard 110 for dimensions previously given), the lower boundary of inhaust cavity will fall upon the line 693, while in the case of the exhaust cavity *d*, its upper limits will be upon the line *x333* and its lower limits upon the line 115 733.

Then, in respect of the present or initial position of the valve, as shown in Fig. 6, the upper boundary of the double piston spacing *s*, the lower edges of the exhaust ports *i*, and 120 the upper boundary of the exhaust cavity *d* will all lie upon the line *x333*.

Further, the lower piston *r* is seen to cover the inhaust ports *h* and the upper piston *q* to cover the exhaust ports *i* of the 125 valve sleeve *g*, so that at this instant, no passage of vapor or of gas can occur between the valve chamber cavities and the engine cylinder, the length of the valve sleeve being such as to cover the valve chamber 130

cavities in any position of the sleeve, and prevent any passage save when the sleeve ports are uncovered by the double piston, when said ports are in line with said cavities.

5 Lastly, it may be noted that the engine piston is at the upper limit of its stroke and reversing (reversal being indicated by double-pointed arrows) the double piston is 10 also at the upper limit of its travel and reversing, while the valve sleeve is still ascending.

15 Having discussed the assembly and described the initial positions of the valve parts, the complete cycle of the valve's operations may be easily traced.

20 As the double piston begins to descend and the split sleeve continues to rise, the piston spacing s will begin to uncover the 25 inhaust ports h of the sleeve and the latter ports being abreast of the inhaust cavity c , there will occur a passage of vapor from this cavity, which vapor will pass into the spacing s and thence down through the hollow piston r and into the engine cylinder, the exhaust ports i , meanwhile, being kept 30 covered by the upper piston q . The actual "inhast opening" will occur with the double piston at zero of its crank's rotation, and the valve sleeve at 330 degrees of its eccentric's rotation, as shown in Fig. 6, but for the sake of ocular clearness, Fig. 8 is 35 drawn to show the double piston at 10 degrees of rotation and the valve sleeve at 340 degrees of rotation in which the sleeve is rising, the piston is falling, and the in- haust is opening.

40 Succeeding figures of the valve positions will be sufficiently clear without the use of reference characters other than those relating to reference lines and rotational positions, or to positions in travel.

45 Fig. 9 shows the valve in the position "inhast full open," double piston at 6 degrees, and valve sleeve at 36 degrees, the double piston and the sleeve both falling, the former the faster, and with the lower boundary of the piston spacing and lower edge of inhaust port approximately in the 50 line 191, and as before, the exhaust port remaining covered.

55 Fig. 10 represents the valve when approaching "inhast closing" and is taken at the end of the inhaust stroke of the engine and with the valve piston at 90 degrees and valve sleeve at 60 degrees, both falling. The valve piston continues to gain on the sleeve until the piston reaches 105 degrees and the sleeve 75 degrees.

60 Before this point is reached, however, and when the double piston is at 100 degrees and the sleeve at 70 degrees of rotation, the piston spacing clears or passes the inhaust port, and we get the actual "inhast closing" positions, as shown in Fig. 15. The

upper boundary of the piston spacing and the lower edge of the inhaust port are then in register and upon the line 840. The engine piston is now upon its compression stroke and the above position equals, 70

$\frac{173}{1000}$ of this stroke.

When the valve sleeve reaches 80 degrees of rotation, and the double piston 110 degrees, the inhaust ports of the sleeve overtake the piston spacing upon the line 1009, at which instant, however, the ports clear the lower edge of the inhaust cavity, line 693, so that no leakage can occur between 80 the engine cylinder and this cavity. This is a critical feature in the construction.

Fig. 11 shows the valve positions at the "explosion point," the latter being assumed to occur without either retardation or advance, viz: at the instant the engine piston is changing from compression stroke to power stroke, and with the double piston at 180 degrees and the valve sleeve at 150 degrees. The double piston in this figure is 90 reversing, the sleeve is falling, and the valve chamber cavities are both sealed.

"Exhaust opening" occurs with the double piston at 268 degrees and the valve sleeve at 238 degrees, both rising, but for clearness, 95 Fig. 12 shows the double piston at 270 degrees and valve sleeve at 240 degrees. The piston spacing at this instant and at the instant previously mentioned, is slightly in advance of the exhaust port of the sleeve in the 100 upward travel, and as the upper edges of the latter ports register with the lower edge of the exhaust cavity, line 733, exhaust sets in. This moment equals .966 of the explosion or working stroke of the engine, but in 105 the general design, this particular moment may be shifted greatly, either earlier or later; through the lowering or the raising of the lower boundary of the exhaust cavity.

Fig. 13 shows "exhaust full open," the 110 double piston being at 310 degrees, and the valve sleeve at 280, the latter having gained upon the former, so that the exhaust port has overtaken and reached the position abreast the piston spacing, the lower edge of 115 exhaust port and the lower boundary of piston spacing now lying substantially upon the line 357, with the sleeve now gaining upon the piston.

Here, it should be noted that in rising, the 120 lower edge of the lower piston covers the lower edges of the inhaust ports of sleeve on lines 1024 and 1007 respectively, so that at the critical phase when the upper edge of inhaust port registers with lower edge of in- haust cavity, double piston 310 degrees and valve sleeve 280, there can occur no leakage from valve chamber to inhaust cavity, during the exhaust stroke of the engine. In 125 Fig. 13, the inhaust port will be seen as 130

UNITED STATES PATENT OFFICE.

CHARLES FRANKLIN BRADBURN, OF DELMER, ONTARIO, CANADA.

VALVE.

1,215,769.

Specification of Letters Patent. Patented Feb. 13, 1917.

Application filed July 7, 1916. Serial No. 108,013.

To all whom it may concern:

Be it known that I, CHARLES FRANKLIN BRADBURN, of the village of Delmer, in the county of Oxford and Province of Ontario, 5 Dominion of Canada, have invented certain new and useful Improvements in Valves; and I hereby declare that the following is a full, clear, and exact description of the same.

- 10 The ordinary type of sleeve valve engine under rapid changes in load and consequent fluctuations in thermal conditions, develops variations in the rates of expansion of the sleeves, cylinder walls, liners, etc., of the 15 engine, and from this condition, serious binding effects result between these parts, as well as from carbonization and from oil residue in combustion engines.

Moreover, the heavy gas pressures to 20 which sleeves, filling the entire engine cylinder are subjected, the severe raking effect of the contained engine piston, the fact that such sleeves must be actuated through connections acting to one side of the sleeve, and 25 the further necessity of the valve mechanism being entirely within the engine cylinder, all constitute serious disadvantages.

A principal object of the present invention, a piston and sleeve valve for any type 30 of engine, and particularly for internal combustion engines, is the retention of all the advantages of the sleeve type of valve, and the avoiding of the above-mentioned, and certain other, inherent disadvantages.

35 Briefly, the invention comprises a valve casing, containing a cylindrical valve chamber, mounted upon an engine, and having two ports preferably arranged as annular cavities, inhaust and exhaust, the planes 40 containing the ports being displaced axially of the chamber in respect of each other, a valve sleeve reciprocating within the valve chamber and carrying two semi-annular rows of ports, inhaust and exhaust, with a 45 spacing between them axially of the sleeve, having a correspondence with those of the valve casing, and a double piston reciprocating within the valve sleeve, one piston being an ordinary or closed piston with piston 50 or packing rings, and the other piston being hollow or open, comprising a spider

carrying rings, there being a spacing between the pistons equal to the spacing between the two semi-annular rows of ports. When the spacing between the pistons registers with a line of ports in the sleeve and with one of those of the valve chamber, the inhaust or exhaust occurs, as the case may be.

The double piston and the split sleeve are driven by eccentrics, or by crank and eccentric respectively, from a half speed valve shaft above them, the crank of the piston being set in advance of the eccentric of the sleeve, this angular advance equaling, preferably, 30 degrees of rotation.

In the drawings:

Figure 1, is a longitudinal section showing a cylindrical valve chamber mounted upon an engine cylinder;

Fig. 2, is an elevational view of the split 70 valve sleeve which operates in the valve chamber, showing two rows of ports, one for inhaust and the other for exhaust;

Fig. 3, is a plan view of the upper end of the valve sleeve shown in Fig. 2;

Fig. 4, is an elevational view of the double piston which operates within the valve sleeve;

Fig. 5, is a plan view of the lower end of the piston;

Fig. 6, is a sectional elevation showing the valve assembly and its connections, in the initial phase of the valve's cycle of action;

Fig. 7, is a fragmentary elevation of the valve connections, at right angles to Fig. 6;

Fig. 8, is a sectional view showing the double piston at 10 degrees of rotation and the valve sleeve at 340 degrees, during the cycle of action;

Fig. 9, is a sectional view showing the 90 valve positions, with the double piston at 6 degrees and valve sleeve at 36 degrees;

Fig. 10, is a sectional view with the piston at 90 degrees and the valve sleeve at 60 degrees;

Fig. 11, is a sectional view with the piston at 180 degrees and the valve sleeve at 150 degrees;

Fig. 12, is a sectional view with the piston at 270 degrees and the valve sleeve at 240 degrees;

Fig. 13, is a sectional view with the piston

55

60

at 310 degrees and the valve sleeve at 280 degrees;

Fig. 14, is a sectional view with the piston at 350 degrees and the valve sleeve at 320 degrees; and,

Fig. 15, is a sectional view with the piston at 100 degrees and the valve sleeve at 70 degrees.

Like characters of reference refer to like parts throughout the specification and drawings.

In these figures, the direction of motion of the valve piston and sleeve and their connections, the engine piston, and the passage of vapor or of gas, are all indicated by suitable arrows.

The drawings are to some extent diagrammatic and not necessarily working drawings, and for this reason it has not been thought necessary, for example, to show a cooling system or other of the less essential features of an internal combustion engine, neither is the driving gear leading to the valve shaft shown, as such gear is not an integral portion of the invention.

In Fig. 1, *a* is the cylindrical valve casing, containing a valve chamber *a'*, mounted upon the engine cylinder *b* and having two ports, preferably arranged as semi-annular cavities, *c* being the inhaust and *d* being the exhaust, these ports being separated by partitions *e*. The valve chamber is open at the top to facilitate cooling, though this is not essential, and carries a yoke *f* which furnishes bearings for the valve rods.

In Figs. 2 and 3, is shown the valve sleeve *g*, carrying two rows of ports, *h* for inhaust and *i* for exhaust, with a spacing axially of the sleeve between the rows equal to the depth of the double piston spacing. This sleeve is split along a diametral vertical plane *j*, extending from the lower edge of the sleeve upwardly to the drillings *k* near the upper edge. The purpose of this feature is to give to the sleeve an approximation of the properties of a piston ring, at least beneath the points of drilling, so that, in part because of its elasticity, and in part because of internal gas pressure, there may be no leakage between the sleeve and the wall of the valve chamber, and no binding between the same because of inequalities in expansion. The above feature is extremely important, though not an essential element of the invention.

The sleeve *g* is provided at its upper extremity with an irregular-shaped member *l* which constitutes a reinforcing band or collar carrying a lunular-shaped web *m*, having a bushing *n* which forms an attachment for the rod *o*, which latter carries a connection or bearing *p* for the driving eccentric rod.

In Fig. 4 is shown the double piston, of which the upper piston *q* is closed, and the lower piston *r* is hollow or open, *s* being the

spacing between the two pistons and *t* the piston rod having a bearing *u* for the connecting rod from the driving crank.

Fig. 5 shows the lower end of the lower piston, *t* being the piston rod, *v* the spider and rim, and *w* the piston rings. The piston *r* is adjacent to the lower or engine end of the valve chamber and is made hollow for the free passage of the vapor and gas between the piston spacing and engine cylinder.

A complete understanding of this invention is practically impossible unless definite relative values be assigned to the more essential valve parts and to the movements of the same, and while different relative values might be chosen in the manipulation of the times of inhaust closing and exhaust opening, the former through changes in the location of the lower edges of the inhaust ports of the sleeve, and the latter through changes in the location of the upper edges of the exhaust ports, the other edges in each case remaining unchanged, and still greater changes effected through the shifting of the angular distance between the crank of the valve piston and the eccentric of the valve sleeve, the values here given are those which at the present time it is believed will give the highest average results or efficiency in high speeds, and this, of course, must take into consideration, fuel consumption, speed, flexibility, stresses and wear.

Assuming the radius of the valve crank and the throw of the eccentric to be 1000 units of space, and the angular distance between crank and eccentric to be 30 degrees, the piston being in advance, then the valve displacement, or displacement of sleeve and of piston, will be 1000 units each, or the valve travel 2000 units, and the piston being in advance of the sleeve, the respective lines of travel of these two principal moving parts may be made to overlap, the piston and sleeve moving at certain times in opposite directions and at certain other times in the same direction and with varying relative speeds, as will become more apparent in discussing the valve assembly and the valve positions in operating throughout the complete cycle of the valve's action.

On the above basis of valve travel and angular distance between crank and eccentric, the following will be the relative dimensions of the essential parts of the valve mechanism:

Vertical depth of inhaust cavity of valve chamber equals 827 units;

Vertical depth of exhaust cavity of valve chamber equals 1066 units;

Vertical depth of inhaust ports of valve sleeve equals 316 units;

Vertical depth of exhaust ports of valve sleeve equals 333 $\frac{1}{3}$ units;

Vertical displacement between upper edges 130
